(57) **CLAIM**

We claim the ornamental design for a scrub cap, as shown and described.

DESCRIPTION

FIG. 1 is a front, right perspective view of a scrub cap in accordance with our new design as it may appear when worn with the front portion of the scrub cap in a partially rolled position;

FIG. 2 is a rear, left perspective view thereof as it may appear when worn with the front portion of the scrub cap in a partially rolled position;

FIG. 3 is a rear, left perspective view of the scrub cap of FIGS. 1 and 2 when not being worn;

FIG. 4 is a top, left perspective view thereof;

FIG. 5 is a bottom, front perspective view thereof;

FIG. 6 is a front elevational view thereof;

FIG. 7 is a top plan view thereof;

FIG. 8 is a bottom plan view thereof;

FIG. 9 is a rear elevational view thereof;

FIG. 10 is a left side elevational view thereof, the right side elevational view being a mirror image thereof; and,

FIG. 11 is an exploded view of unassembled components of the scrub cap in a flat plane with no depth or contour. The different dotted stippling patterns in FIGS. 1-11 represent a contrast in appearance of material.
